LECHER WIRE SYSTEM

Martin Vieweger, Berlin, Germany; vested in the
Alien Property CustodianApplication June 14, 1939, Serial No. 279,128
In Germany June 22, 1938

7 Claims. (Cl. 178—44)

In ultra short wave apparatus it is not possible for the oscillatory circuits to be formed of so-called concentrated capacities and inductances, because the wave-lengths are too small to allow of arranging a concentrated capacity or condenser. Also, in the case of very short wavelengths the self-capacities of the coils and the self-inductances of the condensers as well as of the leads thereto are particulars that require consideration in certain respects. Therefore, the oscillatory circuits are formed as Lecher wire systems, that is to say, systems comprising two wires which are parallel to each other. The length of such circuits is a multiple of $\lambda/4$, where λ is the operative wavelength. Since the Lecher wire system has to be tuned it has previously been necessary to provide for varying the effective length of the Lecher wires to effect the tuning.

According to the invention the Lecher wire system is not altered in this way, thus being left constant in length. In a preferred embodiment of the invention the free ends of the Lecher wires are bent into a semicircular shape and a disc or plate is arranged to be inserted into the interspace of the wire ends so shaped. This disc, which to such end may be rotatable or slidable, has a dielectric constant ϵ greater than that of air, a fact which may be expressed by the relation $\epsilon > 1$. The arrangement is such that the disc does not contact with the Lecher wires. The disc may, for instance, be of a ceramic material of the kind having a high ϵ -value and small losses, or may consist of polystyrene or the like. By inserting between the Lecher wires a disc of this type the tuning may be varied to accord with frequencies lower than in the case of Lecher wires not influenced by such a dielectric.

For variations relative to larger frequency ranges the invention provides a number of semicircular wire stages each comprising semicircular wires and a disc adapted to be inserted into the interspace thereof to tune such stages in the aforesaid manner.

In the accompanying drawing, Fig. 1 is a diagrammatic view showing an elementary form of systems as provided by the invention, Fig. 2 is a diagrammatic representation illustrating a number of such elementary forms, these constituting stages adapted to be interconnected, Fig. 3 is a diagrammatic view showing a modification of the arrangement represented in Fig. 1.

L denotes Lecher wires which in Figs. 1 and 2 are shown to be semicircular at their free ends. A rotatable disc H is arranged to be turned

into the interspace of these wire ends without contacting therewith. In order to provide for interconnecting stages of the kind represented in Fig. 1, switches S, Fig. 2, may be arranged to allow of selectively elongating or shortening the wires L by either adding or disconnecting semicircular divisions L'. Each such division has a disc H for tuning it.

The constructional forms illustrated in Figs. 1 and 2 are susceptible of many variations. For instance, instead of the discs H wedge-shaped bodies may be shifted into the interspace of the free ends of the Lecher wires in a manner to continually increase the effective ϵ -value. Also, 15 a plate as shown in Fig. 3 may be provided, which is composed of two parts A, B each having an ϵ -value different from that of the other part. This plate, adapted to be moved in different directions as indicated by the arrows, enables 20 the effective ϵ -value to be continually increased.

What is claimed is:

1. A Lecher wire system comprising a pair of Lecher wires and means for effecting continuous tuning of said Lecher wires by varying the capacity per unit length of said wires from one 25 end thereof comprising a body having a dielectric constant greater than unity mounted for selective adjustable insertion between said wires from one end thereof and along the length thereof, said member being in insulated relation with respect to said wires.

2. A system according to claim 1, in which the free ends of the Lecher wires are semicircular and in which the said body is a rotatable disc.

3. A system comprising a pair of Lecher wires, pairs of conductors arranged in line with these wires and adapted to be interconnected serially therewith, switches for selectively interconnecting said Lecher wires and conductors, a body 40 adapted to be inserted into the interspace of these Lecher wires, and other bodies each allotted to one of the said pairs of conductors and adapted to be inserted into the interspaces of such conductors, the said bodies having a dielectric constant greater than that of air.

4. A system according to claim 3, in which the said pairs of conductors are semicircular.

5. A system according to claim 3, wherein the bodies allotted to said pairs of conductors are 50 rotatable discs.

6. A system according to claim 1, in which the said body is of a ceramic material having a high dielectric constant and small losses.

7. A system according to claim 1, wherein the 55 said body consists of polystyrene.
